United States Patent Office.

THOMAS LEWIS, OF MALDEN, MASSACHUSETTS.

Letters Patent No. 68,629, dated September 10, 1867.

IMPROVEMENT IN SYRINGES.

The Schedule referred to in these Letters Patent and making part of the same.

TO ALL WHOM IT MAY CONCERN:

Be it known that I, THOMAS LEWIS, of Malden, in the county of Middlesex, and State of Massachusetts, have invented an Improvement in Enema Syringes, of which the following is a full, clear, and exact description, reference being had to the accompanying drawings, making part of this specification, in which—

Figure 1 is a section through the centre of a syringe having my improvement applied thereto.

Figure 2 is an elevation (enlarged) of the end of the inlet tube which contains the valve.

Figure 3 is a detail, (enlarged,) to be referred to.

My invention relates particularly to that class of enema syringes provided with an elastic bulb, operating in connection with valves placed within the metallic connections of the syringe. These valves frequently drop out and are lost when the connections are unscrewed for the purpose of cleansing the parts or packing in the box, to avoid which the valves have sometimes been enclosed in separate chambers. To form these chambers, however, it becomes necessary to have two screw joints in each connection, which renders the syringe complicated and expensive.

My invention has for its object to overcome these difficulties, and consists in retaining the valve in place and preventing it from dropping out by means of a perforated plate or disk, which is screwed down into the connection over the valve, the liquid passing freely through it as required.

To enable others skilled in the art to understand and use my invention, I will proceed to describe the manner in which I have carried it out.

In the said drawings, A represents the elastic bulb of the syringe, B the induction pipe, and C the metallic connection between the two. The upper end of the pipe B is enlarged, forming a chamber, which contains the induction valve *a*, a female screw, *b*, being formed within the chamber, by means of which the pipe is secured to the connection C, and may be removed at pleasure. *c* is a perforated disk or plate, of metal or other suitable material, which is made to fit the screw *b*, and when in place, as seen in figs. 1 and 2, serves to confine the valve *a* in its place, and prevent it from dropping out and being lost on the pipe B being unscrewed and removed from the syringe, and it will be seen that the perforations in the disk *c* allow the liquid to pass freely through it, as required. The disk *c* may be readily turned to screw it down into place, or remove it when it is desired to take out the valve, by inserting the square end of a piece of wood or other article which may be at hand into the rectangular opening *d*.

By means of this arrangement all liability of losing the valve is avoided, while the cost of the disk *c* is very trifling, and but one screw joint is rendered necessary in each connection. A similar disk *c* may be placed in the branch D, over the eduction valve *e*, if desired, although I do not deem it of as much importance, as the connection at this point is not often unscrewed, while the induction pipe B is removed each time the syringe is placed in its box. By the use of the disk *c* I am enabled to make a syringe with a long metallic inlet pipe, B, as portable as those syringes which are furnished with two elastic tubes, as the pipe B may be made removable, and when unscrewed, so that it can be placed in the box, the valve is held securely in place without danger of being lost. I do not confine myself to the use of the disk *c* in the particular variety of syringe shown, as it is evident that it may be applied to advantage wherever loose valves are employed.

I am aware of the nature of the patents issued to H. D. Lockwood, August 25, 1863, and to Morris Mattson, February 5, 1867, and do not claim their mode of construction, but what I claim as my invention, and desire to secure by Letters Patent, is—

The removable perforated disk *c*, with the male screw-thread on its outer edge adjusted to fit the female screw-thread *b*, substantially as described and for the purpose set forth.

THOMAS LEWIS.
